WILLIAM WEIR HENRY, OF WOLLASTON, AND ALTON E. STEVENS, OF ATLANTIC, MASSACHUSETTS, ASSIGNORS TO S. H. COUCH CO. INC., OF ATLANTIC, MASSACHUSETTS.

MAIL-BOX.

1,173,961.

Specification of Letters Patent. Patented Feb. 29, 1916.

Application filed January 12, 1915. Serial No. 1,740.

To all whom it may concern:

Be it known that we, WILLIAM WEIR HENRY, of Wollaston, and ALTON E. STEVENS, of Atlantic, citizens of the United States, and residing at the above places in the county of Norfolk and State of Massachusetts, have invented certain new and useful Improvements in Mail-Boxes, of which the following is a specification.

10 This invention relates to boxes or cabinets, such as, for instance, mail boxes, and has particular reference to the closure and the mechanism for mounting the same, although there are other features which come within 15 the scope of our invention, as will later appear.

In the drawings, which illustrate our invention as applied to mail boxes mounted in series on a single face-plate, Figure 1 is a 20 side view in vertical elevation. Fig. 2 is a front view in vertical elevation. Fig. 3 is a section on line 3—3 of Fig. 2, with one of the doors partly open and in elevation. (In 25 this view, liberty has been taken to hinge the doors at the side opposite to that shown in Fig. 2.) Fig. 4 is a section on line 4—4 of Fig. 2. Figs. 5, 6 and 7 are sections, respectively, on lines 5—5, 6—6 and 7—7 of Fig. 4.

30 Our principal object has been to produce a box with a plain front and without the usual projections and corners for forming the hinge, jamb or lock, and to form a closure for same in which all the mounting 35 parts are concealed within the box. As one of the novel features to this end, we have shown a swinging door so pivoted to the box that a small portion swings inward when the main portion swings outward, this 40 arrangement permitting a door pintle that is entirely concealed.

The wall-plate 1 is struck from sheet metal so as to give the appearance of a plate of added thickness and is formed with a 45 series of screw-holes 2 by which means the plate 1 is secured to a suitable framing, not shown. The openings 3, 4 and 5, in this case all similar in outline, permit access to a 50 series of inclined boxes 6, 7 and 8, made preferably of sheet metal and formed to snugly adjoin each other so as to economize space within the wall upon which the wall-plate 1 is secured, and particularly the perpendicular space from said plate. These 55 boxes are secured to plate 1 by means of

a series of turned ears or lugs 9, on said plate, which fit snugly within the respective boxes, and also by a pair of metal strips 10, 10, positioned along the outsides of the boxes. The pintle 11, on which all the doors 60 are hung, passes through holes in the boxes and also through other ears or lugs 13, formed integral with plate 1, and is thus entirely concealed back of plate 1.

The formation and mountings of the 65 doors present the principal features of novelty in our invention, and as they are all shown identical in construction, but one need be described.

In forming our door of sheet metal, it is 70 desirable, both for purposes of economy and efficiency, that the several parts forming the hinge and other removable portions should be secured by means of ears struck up from the integral with the door. Also, 75 for purposes of neat finish and smooth exterior, it is desirable that none of these ears nor the spaces from which they were struck should be visible from the front or outside. For these reasons, we prefer to form our 80 door with a face sheet 12 which is bent or crimped around the edges of the inside plate 15, which latter may be of heavier and cheaper material. Both sheet 12 and plate 85 15 are formed with top and bottom lugs 16 which are properly perforated for the free passage of pintle 11.

As usual opening 17, for receiving the mail, is covered by a flap 18, pivoted on two 90 lugs 19, struck from plate 15, said flap having an turned lip 20, to insure the holding of said flap against the opening 17 by gravity. Below opening 17, we form another opening 21, guarded inside by a glass 95 window 22, said window being retained by a pair of spring-plates 23 which hook over ears 24, struck up from plate 15, so as to prevent chattering of the window. A similar pair of ears 25 are struck up to engage 100 the upper edge of window 22, the end play of said window being guarded by another pair of ears 26.

The only bolts used in the entire box are those numbered 27 which secure the lock 28, of ordinary construction, to plate 15. The only rivets used (excepting the usual ones found in an ordinary lock) are those numbered 30 and 31, for uniting the boxes to wall-plate 1. The heads of rivets 30 serve as stops for the doors when swung 110

to locked position, and the inturned edge 32, on each of the several openings 3, 4 and 5, serves as a hasp for the bolt 33 of lock 28. (Fig. 4.) Spring-plates 23 are preferably 5 made slightly longer than is necessary to hold window 22 against chattering, and this is to permit a printed or numbered card to be slipped between them and the window to serve as a means of identification that 10 will be visible from the front, but which is secure against disturbance by those who do not possess a key to the door.

We do not limit ourselves to the precise construction shown.

15 What we claim is:

1. In a mail box, a face-plate with a plurality of openings; a plurality of separate, open-ended boxes rigidly secured against said face-plate so their open ends shall each 20 register with one of said openings; and horizontally swinging doors, one for each of said openings and each comprising a stiff, sheet-metal frame with suitable openings, and a flexible sheet-metal veneer rigidly attached to said frame.

2. A mail box comprising a wall-plate with a plurality of openings; a plurality of individual boxes rigidly secured against the rear of said wall-plate and adapted to register with said openings; and a plurality of doors, one for each of said openings, each door comprising a frame with an opening for the insertion of mail matter into its respective box, movable means for closing the 35 opening in said frame, ears struck up from said frame and adapted for the mounting of said movable means, and a flexible metal covering for said frame and rigidly attached thereto so as to conceal said ears from front 40 view and to permit said insertion of mail matter.

3. In a mail box, a face-plate with suitable openings; a series of individual, open-ended boxes rigidly secured against the back 45 of said face-plate, one against each of said openings; and a series of doors adapted to close said openings, each door comprising a stiff, sheet-metal frame with suitable openings, closers for said openings in said frame,

mountings for said closers fast on said 50 frame, and a flexible, sheet-metal covering permanently and rigidly connected with said frame, said covering being adapted to conceal said mountings from front view.

4. In a mail box, a door comprising a 55 frame with suitable openings; a transparent closer behind said frame and adapted to close one of said openings; a movable flap adapted to close the other of said openings; mountings for said closer and said flap 60 formed fast in connection with said frame and visible therethrough; and a flexible metal sheet with openings adapted to register with said openings in said frame, said sheet being permanently and rigidly mounted 65 on the front of said frame and adapted to conceal said mountings from front view.

5. A mail box comprising a wall-plate with a plurality of openings; a plurality of swinging doors adapted to close said openings and provided with apertures for the insertion of mail matter; and a common pintle 70 for said doors; in combination with a plurality of individual, open-ended and inclined boxes adapted to be rigidly secured 75 to the rear of said wall-plate, one independently over each of said openings, all of said boxes being identical in shape and outline.

6. A mail box comprising a wall-plate with an opening; an open-ended, single-compartment and inclined box rigidly secured against the rear of said wall-plate and over said opening; and a door adapted to close said opening and comprising a metal frame with an aperture for the insertion of 80 mail matter, and a flexible sheet metal covering formed around the edges of said frame and fast thereon, said covering having an aperture in register with that of said frame 85 and being adapted to conceal said frame 90 from front view.

In testimony whereof, we have affixed our signatures, in the presence of two witnesses.

WILLIAM WEIR HENRY.
ALTON E. STEVENS.
